(57) **CLAIM**

The ornamental design for a blade of oar, as shown and described.

DESCRIPTION

FIG. 1 is a left side view thereof;

FIG. 2 is a front elevation view thereof;

FIG. 3 is a right side view thereof;

FIG. 4 is a rear elevation view thereof;

FIG. 5 is a top plan view thereof;

FIG. 6 is a bottom plan view thereof;

FIG. 7 is a perspective view of a blade of oar showing my new design; and,

FIG. 8 is a perspective view thereof shown in use.

The broken line showing of the oar is included for the purpose of illustrating environmental structure and forms no part of the claimed design.
